Primary Examiner — Prabhakar Deshmukh(74) *Attorney, Agent, or Firm* — Michael J. Striker(57) **CLAIM**

The ornamental design for a controller for controlling the movement of a robotic arm, as shown and described.

DESCRIPTION

FIG. 1 is a perspective view of a controller for controlling movement of a robotic arm showing my new design;
FIG. 2 is a front elevation view thereof;
FIG. 3 is a rear elevation view thereof;
FIG. 4 is a left side elevation view thereof;
FIG. 5 is a right side elevation view thereof;
FIG. 6 is a top plan view thereof; and,
FIG. 7 is a bottom plan view thereof.

The broken lines indicate unclaimed portions and form no part of the claimed design.
